UNITED STATES PATENT OFFICE.

RUFUS M. STIVERS, OF NEW YORK, N. Y.

CARRIAGE-SEAT.

SPECIFICATION forming part of Letters Patent No. 416,872, dated December 10, 1889.

Application filed April 2, 1889. Serial No. 305,684. (No model.)

To all whom it may concern:

Be it known that I, RUFUS M. STIVERS, a citizen of the United States, residing at New York, in the county of New York and State 5 of New York, have invented certain new and useful Improvements in Carriage-Seats; and I do declare the following to be a full, clear, and exact description of the invention, such as will enable others skilled in the art to 10 to which it appertains to make and use the same, reference being had to the accompanying drawings and to the letters of reference marked theron, which form a part of this specification.

15 This invention relates to improvements in carriages of that class used for both pleasure and business, and sometimes known as "surreys" or "box-buggies," the object being to provide the carriage with an additional seat 20 when desired without detracting from its appearance as a single-seat vehicle when but one seat is required.

To accomplish this result, the panel which forms a part of the seat-back is attached at 25 its lower side to the seat by hinges, and when in place forming a part of the back is secured in position by a suitable bolt or catch at top; but when an additional seat is required this catch is released and the panel 30 turned back, resting upon the top of the body, its cushioned side uppermost, thus forming a seat facing to the rear, the frame of the panel forming the back-support for both seats. In order to form a foot-rest for 35 the persons occupying the back seat, the rear end of the box or body, which is hinged at the bottom, is allowed to fall outward, and is supported at the proper angle by suitable stays. When not required for use as an ad- 40 ditional seat, the back panel is turned up into its place in the back frame, and the rear end of the box-body is also turned up, thus removing all appearance of the additional seat.

45 In the drawings illustrating this invention, Figure 1 is a perspective view of the carriage body and seat arranged as a single-seat vehicle. Fig. 2 is a similar view of the parts as arranged for two seats. Fig. 3 is a longitudinal section through the body, showing the parts in full lines forming a single-

seated vehicle and in dotted lines as arranged for two seats. Fig. 4 is a side elevation showing a modification in the construction of the seat-arms and back-support. 55

In the several figures, A represents the carriage body or box, which may be of any desired form and mounted upon any suitable running-gear. The style preferred, however, is that shown in the drawings—namely, a 60 plain box cut away in front to allow easy access to the seat and provided at the rear with the hinged end-board B, which when dropped is supported in any desired position by the stays a a. These stays may be made of 65 chains permanently attached to the end-board and provided at the opposite end from such point of attachment with hooks a', which connect with the body.

From each side of the body at the ends of 70 the seat C extend upward the side supports D D of the back, connected at top by the cross-piece D', thus forming a frame in which is placed the panel E. This panel is connected at its lower side by the hinges e e to 75 the seat C, and when in an upright position in the frame its upper edge comes in contact with the rabbet on the lower edge of the cross-piece, and is held in place by the box-lock or spring catch-bolt b; but when turned 80 down to form a seat it rests upon the supports b' at each side of the box or upon other suitable devices properly placed to retain it in position. The cross-piece D' may be cushioned upon both sides, so as to form a soft 85 support for the back of the occupants of the seats in both front and rear. The panel E is only cushioned upon one side—namely, that which is to the front when it is in place in the frame, and which forms its top when 90 turned down to make a seat facing to the rear. The rails d d, which form the seat-arms, may be arranged, as shown in Figs. 1 and 2, so as to make arms for both seats, or, as illustrated in the modification shown by 95 Fig. 4, so as to make both arms and standards for the seat and its back. The construction of the several parts may also be varied, as straps or metal rods may be used in place of the chains for supporting the end-board 100 and the style of box may be changed without departing from the spirit of my invention.

Having thus described my invention, I claim as new, and desire to secure by Letters Patent, the following:

As an improvement in carriage-seats, the combination of the hinged panel E, adapted to turn down, thereby forming a seat facing the rear, with the supports b', substantially as shown and described.

In testimony whereof I affix my signature in presence of two witnesses.

RUFUS M. STIVERS.
